Primary Examiner — Susan Bennett Hattan*Assistant Examiner* — Charles Hanson(74) *Attorney, Agent, or Firm* — Knobbe Martens Olson & Bear LLP**(57) CLAIM**

The ornamental design for a dental abutment, as shown and described.

DESCRIPTION

FIG. 1 is a top perspective view of a dental abutment embodying the new design.

FIG. 2 is a first side view thereof.

FIG. 3 is a second side view thereof.

FIG. 4 is a third side view thereof.

FIG. 5 is a fourth side view thereof.

FIG. 6 is a bottom view thereof; and,

FIG. 7 is a top view thereof.

Broken lines are used to illustrate features of the dental abutment which form no part of the claimed design.

1 Claim, 6 Drawing Sheets(56)
